UNITED STATES PATENT OFFICE.

GEORGE E. HUTTON, OF DELPHOS, KANSAS.

HORSE-CHECKING DEVICE.

SPECIFICATION forming part of Letters Patent No. 565,681, dated August 11, 1896.

Application filed January 24, 1895. Serial No. 536,104. (No model.)

To all whom it may concern:

Be it known that I, GEORGE E. HUTTON, a citizen of the United States, residing at Delphos, in the county of Ottawa and State of Kansas, have invented a new and useful Horse-Checking Device, of which the following is a specification.

My invention relates to harness, and particularly to a checking device for use in training or breaking horses, and also designed for use in connection with racing-horses; and the objects in view are to provide an overdraw check which is devoid of means for irritating or chafing the horse upon which it is used; to provide means whereby the bit is caused to draw forcibly upon the roof of the mouth of the animal only when the latter attempts to resist or "fight" the bit; to provide a chin-rest which is capable of yielding to allow freedom of movement of the jaws, whereby the bit, tongue, and lips may be arranged to avoid contact with the teeth; to provide means for causing pressure of the bit against the roof of the mouth when the horse attempts to bear upon the chin-rest; and, furthermore, to provide means for adjusting the nose-band at the desired point upon the bridge of the nose.

Further objects and advantages of this invention will appear in the following description, and the novel features thereof will be particularly pointed out in the appended claims.

In the drawings, Figure 1 is a perspective view of a check constructed in accordance with my invention. Fig. 2 is a detail view of the chin-rest. Fig. 3 is a detail view of the bit. Fig. 4 is a similar view of the sliding loop. Fig. 5 is a detail plan view of the crown-piece.

Similar numerals of reference indicate corresponding parts in all the figures of the drawings.

1 designates a bit, which is provided with check-rings 2 and the forwardly-extending levers 3, which terminate in eyes 4 below the plane of the bit for engagement with the extremities of the chin-rest 5, and the body portion of the bit is upwardly bowed to conform to the shape of the roof of the mouth and is broadened at its center to avoid cutting or bruising the mouth. The chin-rest is

provided, preferably at its center, with an elastic or yielding section 6, to adapt the rest to yield and thereby allow the horse to adjust the bit and his tongue and lips to avoid contact with his teeth, and thereby avoid the restraint which is caused by an unyielding chin-rest when the latter is adjusted to fit closely around the lower jaw.

The nose-band 7 is constructed integral with the draw-straps 8, which pass through the check-rings and after extending through the guides 9 on the crown-piece are attached to the billets which form parts of the check-straps 11, and secured to the center of the nose-band is a central adjusting-strap 12, which also engages a buckle 13 at the center of the crown-piece. Slidably mounted upon the draw-straps is a loop 14, which may be arranged close to the bit or may be elevated to a position adjacent to the crown-piece, and through a clip 15 on this loop extends the central adjusting strap, said clip in the construction illustrated being formed as an integral part of the loop.

The levers to which the chin-rest or strap is attached are designed to equalize the bearing and relieve the pressure of the bit on the roof of the mouth, and with the elastic section which forms a portion of the chin-rest the parts are adapted to yield sufficiently to allow a sufficient amount of freedom of the jaws, and in case of stumbling a horse is enabled to recover without producing a shock, such as is unavoidable if the check and chin-rest are unyielding. When a trotter or pacer breaks, the head is thrown up, and if the check and chin-rest are unyielding the horse is unable to recover as readily as when the chin-strap is yielding, or when a slight freedom of movement of the jaws is permitted. The chin-rest is provided at its extremity with billets and buckles to provide for adjustment to regulate the pressure of the bit on the roof of the mouth and to prevent the tongue from lolling.

A horse usually "side reins," "lugs," or tosses the head, &c., to relieve or alleviate punishment or uneasiness, and therefore a check which imposes continuous pressure upon any part is liable to produce these and other habits which are annoying to the driver; but by constructing the checkrein in a single

piece with the nose-band it acts as a draw-rein and brings the nose-band well down upon the bridge of the nose, and thereby compels the horse to carry his nose out and extend his neck to prevent choking and other evils, and the pressure or "draw" is greater or less, according to whether the animal attempts to bear upon the chin-rest. The extent or degree of draw may be regulated by

10 the adjustment of the sliding loop, to increase which the loop is adjusted downward or toward the nose-band, and to diminish which it is moved in the opposite direction.

The construction and arrangement of the 15 parts of this device prevent pressure upon the muscles of the nostrils or upon the arteries and nerves, and hence does not interfere with the circulation of blood or cause irritation.

20 When a horse learns that the pressure of the bit depends upon the position of his head, and that when the head is held in a certain position the pressure is insignificant, it is obvious that he will depend upon his own exertions rather than upon the checkrein, and hence an easy and graceful position of the head will be the result.

It will be understood that in practise various changes in the form, proportion, and the 30 minor details of construction may be resorted to without departing from the spirit or sacrificing any of the advantages of this invention.

Having described my invention, I claim—
35 1. A horse breaking and driving bit having a bowed and centrally-broadened body portion provided with upturned extremities terminating in check-rings, and downwardly and forwardly curved arms of reduced thickness springing from the upturned extremities of the body portion adjacent to the check-rings and terminating in eyes for engagement by the extremities of a chin-rest, said eyes being below the plane of the body portion of 45 the bit, substantially as specified.

2. The combination with a bit having terminal check-rings and forwardly-extending levers, and a chin-rest connected to the front extremities of said levers, of a nose-band provided with integral extensions arranged to slide in the check-rings and extended to form draw-reins, a check-strap connected to said draw-reins, and means for adjusting the center of the nose-band forwardly and rearwardly upon the nose of the horse, substantially as specified.

3. The combination with a bit having check-rings and a chin-rest connected to the bit, of a nose-band provided with extensions ar-

60 ranged to slide in the check-rings and extended to form draw-reins, a check-strap connected to said draw-reins, and an adjusting-strap attached to the center of the nose-band and extending longitudinally of the nose of the horse between the draw-reins and provided with means for varying its tension to 65 arrange the center of the nose-band at the desired point on the nose of the horse, substantially as specified.

4. The combination with a bit provided 70 with terminal check-rings and forwardly-extending levers, and a chin-rest attached at its extremities to said levers, of a nose-band having integral extensions arranged to slide in said check-rings and extended to form draw-reins, a check-strap connected to the extremities of the draw-reins, and a loop-mounted to slide upon the draw-reins and hold the same together at the point of contact therewith and adapted to be arranged near the nose-band or remote therefrom to vary the upward pressure of the bit and the downward pressure of the nose-band, substantially as specified.

5. The combination with a bit having check-rings, of a nose-band having extensions arranged to slide in said check-rings and extended to form draw-reins, a check-strap connected to the extremities of the draw-reins, and a loop mounted to slide upon the draw-reins at an intermediate point and hold opposite or corresponding parts of said draw-reins contiguous to each other, said loop being adapted to be arranged near the nose-band or remote therefrom to vary the downward pressure of the nose-band, substantially as 95 specified.

6. The combination with a bit having terminal check-rings and forwardly-extending levers, and a chin-rest connected to said levers, of a nose-band having extensions arranged 100 to slide in said check-rings and extended to form draw-reins which are attached to a check-strap, a crown-piece having guides through which the draw-reins extend, a loop mounted to slide upon the draw-reins, and hold the same together at an intermediate point, and a central adjusting-strap attached at one end to the center of the nose-band, extending through a clip on the loop and attached to the crown-piece by a buckle, substantially as specified.

In testimony that I claim the foregoing as my own I have hereto affixed my signature in the presence of two witnesses.

GEORGE E. HUTTON.
